PELVIC TRACTION BELT

Samuel Varco, Buffalo, N. Y.

Application September 11, 1951, Serial No. 246,019

9 Claims. (Cl. 128—75)

1

This invention relates to a pelvic traction belt adapted to be placed around the waist and over the crests of the hip bones, and which is provided with extension straps adapted to be connected to a spreader and weights, so that a patient suffering from an injury to the lower vertebrae or pelvis may be locally immobilized and placed under traction, but otherwise will be free to move his limbs and body.

Buck's extension, which has been widely used for the treatment of injuries to the pelvic region, has been criticized as physiologically inadequate, and also because it substantially immobilizes the patient, induces irritability, and is frequently the cause of derivative ailments such as dermatitis and phlebitis. The present invention provides for the treatment of low back injury without any of these disadvantages. In the following portions of this description, there will be described, with reference to the accompanying drawings, an embodiment of the invention, a practical technique for its use, and a summation of the results which have been obtained in its application to a substantial number of patients.

In the drawings:

Fig. 1 is a side elevation of a patient reposing on a hospital bed, to whom the subject belt has been applied;

Fig. 2 is an end view of the same;

Fig. 3 is an enlarged fragmentary perspective of a standard or frame, suitable for applying traction to the belt;

Fig. 4 is an exterior plan of the belt, with a portion of one traction band broken away;

Fig. 5 is a fragmentary interior plan of the belt; and

Fig. 6 is a perspective of a spreader to which the traction bands and weights are connected.

As best shown in Figs. 4 and 5, the traction belt comprises an abdominal band, generally designated by the reference numeral 11, having an exterior surface 12 which may be of any suitable fabric, such as finely woven cotton. The cloth is cut with opposed upper and lower curved edges 13 and 14 which are generally convex at the ends 15 and 16 and central back portion 17 and are somewhat concave at the lateral or hip bone portions 18 and 19. This formation facilitates smooth fitting to the contour of the body when the belt is applied. It is contemplated that the length of the belt may be varied, so that one may be selected for the proportions of the patient, and that the width of the belt may be such as to overlie the crest of the ilium and the lower vertebrae. The illustrated belt has been copied

2

from one suitable for a patient having a girth of about forty inches, and its width ranges from about six inches to about five and one-half inches. These are satisfactory widths for the majority of cases where application of the belt is indicated.

The fabric 12 is notched at the lateral regions 18 and 19, from the lower edge 14 approximately half way toward the upper edge 13, to provide upwardly pointed triangular recesses in which are sewed elastic inserts or darts 21. Experience has shown that such darts have some advantages over inserts of generally trapezoidal form which extend from edge to edge, although the latter have been used with satisfactory results. The ends of the band are fitted with buckles and tie straps, by means of which the belt may be drawn snugly around the body. Those on the right hand side 16 comprise a pair of straps 22 of webbing, sewed to the edge of the belt, and over which may be slipped conventional over-and-under buckles 23. Between them, on a short loop 24 sewed to the belt, is a complementary hook 25. The left hand side 15 is provided with a pair of hooks 26 and a strap 27, for cooperation with the securing means on the right hand side, as will be obvious from inspection.

It will be noted that the positions of the hooks and buckles are alternated or staggered, so that, in applying the belt, a pull is exerted in each direction, that is, toward the right, and also the left. This has been found helpful in fitting the belt with uniform compression of the body. It is also to be noted that the hooks and straps on the left hand side 15 are set back from the extreme end, to provide a shield 28 which will underlie the right hand end 16, and thus preclude direct contact of the metal parts of the fasteners with the body. The straps 22 and 27, and the shield 28, are of such length—say four to eight inches—that a reasonable range of adjustment is provided, making it unnecessary to have a custom built belt for each patient. The free ends of the straps may be tucked into loops formed by sewing a piece of tape 29 along one end of the belt.

The band 12 is reinforced at the ends 15 and 16 by pieces of webbing 31, extending from edge to edge, and sewn along the edges in the manner indicated by the dotted lines. Two additional reinforcing webs 32 are sewn to the back portion 17, and these are spaced sufficiently so as not to bear directly against the lumbar vertebrae. Additional strips of webbing are sewed to the outer face of the band 11, to provide means for apply-

ing tractive force. These include normally disposed or transverse strips 35 and 36, located at the left and right adjacent the bases of the elastic inserts 21, and on the abdominal side, which are reversely bent at the bottom edge 14 to extend angularly as tension transmitting strips or portions 37 and 38 toward the ends of the belt, and to terminate close to the upper ends of the strips 31. The strips 37 and 38 are sewed to the fabric 12 at their upper portions, as indicated by the dotted lines, but they preferably are not sewed throughout the lower portions 39 and 41. Rather, they are given a certain looseness, as is illustrated by the bowing of these portions in the plan view of

upper ends which are intercon-⁴ng on the footrail 75, and which are interconnected by a crossbar 76. The center of the crossbar is provided with an aperture in which is slily mounted a column 77 having a yoke 78 a upper end, in which is rotatably mounted a pulley 79. The sashcord 62, extending from the s⁵ader 56, passes over the pulley 79 and is tied to the weights 81, as will be readily understood.

10. The patient P is measured with an ordinary belt around the waist at the ⁶ape measure, ⁷parallel to the hip bones. The belt ⁸is placed of the crests of the

average value. Reports received until now reveal that as little as twelve, and as many as thirty, pounds have been used, depending upon the size of the patient and the condition treated.

The invention is indicated in the treatment of substantially all low back skeletal injuries, as well as for sprains in the soft tissue and joints. Herniation of the nucleus pulposum in the lumbar intervertebral spaces—the so-called "slipped disc"—has been treated with gratifying results. Minor fractures of the lumbar processes, and of the sacral and iliac bones, also respond to the present treatment. The tractive pull decreases nerve pressure and relaxes muscle spasm, and the injured region is adequately immobilized. Another application is as adjunctive treatment for low back pain such as occurs in spondylolisthesis.

An analysis of the cases which have been treated to date shows that the invention has a number of desirable advantages, when contrasted to previous procedures applied to the same conditions. A completely immobilized patient rarely retains a good mental outlook or tone for a substantial length of time, and he is, of course, a problem for the attending physicians and the nursing staff. As indicated in Fig. 1, the present belt imposes only local immobilization. The patient may raise and bend his legs and body—he may roll, or be rolled, from side to side. This relative freedom, coupled with the relief from pain inherent in tractive treatment, aids greatly in preserving the patient's morale and general comfort, and of course it greatly simplifies proper nursing care.

Such complications as dermatitis, swelling of the ankles or knee joints, and thrombophlebitis, which heretofore have been experienced with traction imposed by adhesive tape applied to the skin, are fully avoided. The only difficulty which may be encountered is unpleasant pressure on the crest of the ilium, or, with an overly active patient, a similar pressure on the outer surface of the thigh. These complaints, when they occurred, were readily disposed of by inserting small pads of sponge rubber, felt, or the like, between the belt and the afflicted area, whereupon the patient was restored to his attitude of tolerance.

One significant advantage of the present invention is in its ability to enable the patient to be restored to ambulation in a comparatively short period of time. It will be recalled that in techniques requiring the knees to be flexed, even for such short periods of time as a few days or a week, there is some atrophy and stiffening of the thigh muscles known as the quadriceps group. This requires post-operative treatment by way of massage to restore the muscles to a satisfactory condition, and requires that the patient shall be hospitalized and disabled for a much longer period of time than otherwise would be required. This period of prolonged disability is eliminated by the present invention, inasmuch as the patient is free at all times to exercise his limbs.

While the invention has been described with respect to a single embodiment, it will, of course, be understood that the belt may be modified in various details without departure from its basic principles. It is therefore intended that the invention be accorded a scope consistent with that expressed in the following claims.

I claim:

1. A pelvic traction belt for the treatment of low back injuries in human beings, comprising

an abdominal band adapted to encircle the waist of a patient, said band having end portions, adjustable securing means connected to the band at said end portions, said band being of such width as to overlie and extend below the pelvic crests and lower vertebrae, said band having curved upper and lower edges, elastic inserts in said band extending upwardly from the lower edge thereof and at the lateral regions of the band, spaced tension transmitting straps secured to the band at the lateral regions thereof, said straps having portions extending angularly upwardly from the bottom edge toward the front and back of the band, traction strips connected to said tension transmitting straps at the lower edge of the belt, said strips converging to common apices and being of such length as to locate said apices below the lower outer aspects of the thighs of the patients, extension strips connected to each of said traction apices, and means connecting said extension strips in spaced relation for connecting the belt to a source of traction.

2. A pelvic traction belt for the treatment of low back injuries in human beings comprising an abdominal band formed with curved upper and lower edges and free ends adapted to be connected to each other over the abdomen of a patient, tapered yieldable inserts in the band at the lateral portions thereof and extending from the lower edge toward the upper edge, substantially normally disposed transverse tension transmitting straps secured to the belt in spaced relation at said lateral portions thereby to be positionable in front and back of the pelvic crests, angularly disposed tension transmitting straps extending from the normally disposed back straps and extending from the lower edge of the band upwardly toward the back thereof, adjustable traction straps connected to said tension transmitting straps at the lower edge of the belt and converging on each side of the belt to apices positionable below the lower aspect of the thighs, and extension straps connected to the traction straps at said apices.

3. A pelvic traction belt as set forth in claim 2, wherein there are additional angularly disposed tension transmitting straps secured to the band and extending from the bottom edge of the band and from the front normally disposed transverse tension straps, forwardly toward the upper edge, said additional straps being connected to said traction straps.

4. A pelvic belt as set forth in claim 3, together with transverse reinforcing strips secured to the back of the band at the region thereof positionable adjacent the lumbar vertebrae.

5. A pelvic traction belt for the treatment of low back injuries in human beings, comprising an abdominal band formed with upper and lower edges and free ends adapted to be secured to each other over the abdomen of a patient, said belt being of such width as to overlie and extend below the pelvic crests and sacral region, said band having lateral regions adapted to overlie and bridge the crests, yieldable inserts in said band at said lateral regions and extending from the lower edge of the band to at least substantially half way to the upper edge, pairs of tension transmitting straps secured to the band on either side of the bases of said inserts, one strap of each rearmost pair extending angularly toward the upper edge of the band to the lumbar region thereof, one strap of each foremost pair extending angularly toward the upper edge and the ad-

7 jacent free end, loose loops in said angularly extending tension transmitting straps, traction straps connected to said pairs of tension straps at the loop portions thereof, said traction straps converging to common apices positionable below the lower outer aspects of the thighs, and extension straps connected to the traction straps at said apices and being of such length as to project beyond the feet when the legs are straight.

6. A pelvic traction belt for the treatment of low back injuries in human beings, comprising an abdominal band having curved edges and free ends adapted to overlap each other over the abdomen of a patient, hooks and buckle straps secured to and adjacent said ends whereby the band may be drawn tightly around the waist with one end overlapping the other to provide a protective shield, said band being of such width as to overlie and extend below the pelvic crests and lumbar region, tapered yieldable inserts in said band at the lateral portions thereof and extending upwardly from the bottom edge into the body of the band, said inserts being so positioned with respect to the ends and back of the band as to be positionable over the pelvic crests, pairs of traction straps connected to the band in spaced relation at the lateral portions thereof so as to be positionable at the front and back of said crests, the traction straps on each side converging to apices positionable adjacent the lower outer aspect of the thigh, extension straps connected to the traction straps at their apices and being of such length as to project beyond the feet of the patient when the legs are straight, and tension transmitting straps connected to the band and to the traction straps to transmit a pull exerted on said traction straps to the regions of the body above the pelvic crests and the lowermost vertebrae.

7. A pelvic traction belt assembly for the treatment of low back injuries in human beings, comprising a fabric abdominal band adapted to be positioned around the waist of a patient and formed with curved edges to substantially conform the band to the contour of the body, said band being cut away along the bottom edge at the lateral portions thereof, elastic inserts sewn in the band at the cut-away areas, tension transmitting strips sewn to the band and extending from the upper edge thereof diagonally from the back to the lower edge adjacent the rear ends of the inserts, other tension transmitting strips sewn to the band transversely thereof on either side of the inserts, pairs of traction straps adjustably connected to the tension transmitting strips, said traction straps converging to apices on either side which are positionable adjacent the lower thigh of the patient, extension straps connected to the traction straps at their apices and being of such length as to project beyond the feet of the patient, and a spreader bar provided with means for adjustably securing the ends of the extension straps and with means for attaching traction weights thereto, said securing means being spaced a sufficient distance that tractive effort applied to the bar will be applied to the pelvic and lumbar regions.

8. A pelvic traction belt for the treatment of low back injuries in human beings, comprising a substantially non-elastic fabric band adapted to be positioned around the waist of a patient,

5 said band having curved edges to enable said band to conform substantially to the contour of the body, said band being of such width as to overlie and extend below the pelvic crests and lower vertebrae, tie strings and buckles at the ends of the band for securing the same to the body, reinforcing strips sewn to the band between the edges at the end portions, pairs of tension transmitting strips sewn across the band in spaced relation at the lateral regions thereof, angularly disposed strips sewn to the band from the back upper edge to the back strip of said pairs and from the abdominal portions of the band to the front strip of said pairs, clasps connected to said strips at the junctions thereof at the lower edge of the band, additional strips sewn to the band in spaced relation at the back thereof to be positionable on either side of the lower vertebrae, said band being notched inwardly from its lower edge at the lateral regions, elastic inserts sewn to the band at the notched lateral regions, traction straps connected to said clasps and converging to apices on either side of the band, extension straps connected to the traction straps at said apices, and a facing of soft and non-irritating material sewn to the inner surface of the band.

9. A pelvic traction belt for the treatment of low back injuries in human beings, comprising an abdominal band adapted to encircle the waist 30 of a patient, said band having secured thereto ties for tightening the band around the waist, said band being of such width as to overlie the pelvic crests and lower vertebrae and also to extend below the said pelvic crests, pairs of traction 35 straps connected to said band at each of the lateral portions thereof and being spaced at the points of connection to lie directly in front and back of the pelvic crests, a pair of tension transmitting straps secured to the band and extending angularly from the lower edge thereof toward the upper edge and toward the back of the band, the back strap of each pair of traction straps being connected to one of said tension transmitting 40 straps, each of said pairs of traction straps converging from their points of connection to the band toward an apex which, when the band is applied, will be below the thigh of the patient, said pairs of traction straps having extension 45 straps connected thereto at their apices, said extension straps being of such length that their ends will be below the foot of the patient when the leg is straight, said ends being adapted to be connected in spaced relation to a spreader bar.
